(57) **CLAIM**

The ornamental design for a rail road tie plug tool, as shown and described.

DESCRIPTION

FIG. 1 is a front perspective view of a rail road tie plug tool, showing our new design;

FIG. 2 is a top plan view thereof;

FIG. 3 is a bottom plan view thereof;

FIG. 4 is a right-side elevation view thereof;

FIG. 5 is a left side elevation view thereof;

FIG. 6 is a front elevation view thereof; and,

FIG. 7 is a rear elevation view thereof.

1 Claim, 3 Drawing Sheets
